(57) **CLAIM**

The ornamental design for a bow sight, as shown and described.

DESCRIPTION

FIG. 1 is a front elevation view of my design for a bow sight that is vertical positioned and depicting a sight aperture having a relatively oval configuration.

FIG. 2 is a back elevation view of the bow sight of FIG. 1.

FIG. 3 is a right side view of the bow sight of FIG. 1.

FIG. 4 is a left side view of the bow sight of FIG. 1.

FIG. 5 is a top elevation view of the bow sight of FIG. 1; FIG. 5 depicts a bow string aperture vertically extending through the bow sight.

FIG. 6 is a bottom elevation view of the bow sight of FIG. 1; FIG. 6 depicts the bow string aperture of FIG. 5 vertically extending through the bow sight.

FIG. 7 is a front elevation view of the bow sight of FIG. 1, but with the bow sight vertically positioned such that a vertical axis is “tilted” to cause the sight aperture configuration to transform from oval to circular.

FIG. 8 is back elevation view of the bow sight of FIG. 7.

FIG. 9 is a right side elevation view of FIG. 7 depicting the vertical “tilt” of the bow sight of FIG. 7; and,

FIG. 10 is a left side elevation view of FIG. 7 depicting the vertical tilt of the bow sight of FIG. 7.
